SANDING MACHINE

William D. R. Stovall, Jackson, Miss.

Application May 26, 1936, Serial No. 81,921

7 Claims. (Cl. 51—170)

The invention relates to a sanding machine and more particularly to a readily movable sanding machine.

The primary object of the invention is the provision of a machine of this character, wherein the sanding belt is balanced and is adjustable with relation to the work to be operated upon thereby and by reason of the character of the supporting frame of the machine the sanding belt can be brought to the work, as for example, school desks arranged within a school room or other articles of furniture fixedly disposed and in the working of the machine the surface to be cleaned or smoothed will be promptly acted upon by the sanding belt, the loose material such as wood dust or the like being collected during the operation of the machine.

Another object of the invention is the provision of a machine of this character, wherein the construction thereof is novel in its entirety and is especially designed for resurfacing school furniture where the latter becomes marred, scratched, scarred or otherwise disfigured and dirty and in the operation of the machine the surface disfigured can be cut down easily and rapidly and the original smoothness, cleanliness and texture restored.

A further object of the invention is the provision of a machine of this character, wherein the sanding belt is operated through a power motor or motors and such belt will straddle the furniture to be reconditioned where such furniture is permanently fixed in place.

A still further object of the invention is the provision of a machine of this character, which is simple in its construction, thoroughly reliable and effective in its operation, readily and easily handled, the sanding belt being balanced through a novel hanging therefor, the said belt being maintained clean during the working of the same and also that is inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is an elevation of the machine constructed in accordance with the invention, a portion thereof being broken away.

Figure 2 is a vertical transverse sectional view through the machine.

Figure 3 is a horizontal sectional view taken on the line 3—3 of Figure 1.

Similar reference characters indicate corresponding parts throughout the several views in the drawing.

Referring to the drawing in detail, the machine comprises a pair of bed trucks 10, these being equipped with rollers or wheels 11 to render the same mobile and rising from the said trucks is an inverted substantially U-shaped stand including the vertical tubular uprights 12 and a cross top rail 13, respectively, the uprights being joined to the rail 13 through T couplings 14 while said uprights 12 are made fast at 15 to the trucks 10.

Disposed crosswise of the stand is an endless sanding belt 16 supported upon rotatable relatively broad pulleys or belt wheels 17, both having their hubs 18 made fast to driven shafts 19 which are journaled in bearings 20 adjustably fitting slide hangers 21. The hangers 21 are fitted for sliding movement upon the uprights 12 and the said belt 16 is sustained in a horizontal plane slightly forward of the stand, the trucks 10 being spaced the required distance apart so as to permit an article of furniture to pass therebetween and have the belt 16 brought into working position relative to such article of furniture.

Upon the trucks 10 are electric motors 22 each having its driving shaft 23 connected with the driven shaft through a flexible power shaft 24 so that the endless belt 16 will be driven directly from the motors 22.

The bearings 20 are adjustable at 25 for permitting the tightening and slackening of the belt 16.

Arranged within each upright 12 is a coiled tensioning spring 27, its lower end being fixed at 28 to the companion truck 10 and the upper end fixed to a sprocket chain 29 which is trained over a sprocket wheel 30 fixed to a cranked shaft 31, this being rotatably fitted in angled bearing brackets 32 secured to the top rail 13 at opposite ends thereof and outside of the stand. These sprocket chains 29, each is engaged with a sprocket wheel 33 journaled in a bearing 34 fixed to and rising from the bearing 20 next thereto. The sprocket wheel 33 is straddled by a forked handle 35 carrying a latch 36 for engagement with the said wheel 33 so that it can be manually turned for imparting movement to the chain 29 which in conjunction with the spring 27 affords a balance for the belt 16 and the pulleys or belt wheels 18 carrying the same. By operating the handle 35 the hangers 21 can be raised or lowered on the uprights 12 of the stand to locate the belt 55

16 with respect to a piece of work to be operated upon thereby.

About one end of the belt 16 is a dust guard 37 which extends about the said end and is fitted with a delivery conduit 38 of a vacuum operated dirt and dust collector 39, its suction wheel 40 being driven through a belt and pulley connection 41 with the motor shaft 23, there being but one of these collectors associated with the machine so that dust and dirt removed by the sanding belt 16 will be caught in the guard 37 and collected by flow thereof through the conduit 38 to and in the collector 39. This collector has the collector bag 42 for the reception of dirt and dust as is common in vacuum cleaners.

The crank 43 of the shaft 31 constitutes a handle for the convenient turning of this shaft 31 so that by operating such handle the sanding belt 16 can be manually adjustable for light or heavy sanding operation with respect to a piece of work operated upon in that the chains 29 can be moved and such chains are constantly under the tension of each spring 21 connected therewith. The sprocket wheel 35 on each bearing 20 permits the setting of the sanding belt for a determined balanced adjustment thereof while by operating the crank 43 the belt will be brought into a position for light or heavy sanding operation upon a piece of work being acted upon thereby.

30 What is claimed is:

1. A machine of the character described comprising a wheeled trucked stand having an opening for the reception of a piece of work when permanently fastened in place, sanding mechanism on the stand and including an endless sanding belt for operation upon the work when received by the stand, power means on the trucks of said stand and operating the sanding mechanism, and spring tensioned balancing means connected with said sanding mechanism.

2. A machine of the character described comprising a wheeled trucked stand having an opening for the reception of a piece of work when permanently fastened in place, sanding mechanism on the stand and including an endless sanding belt for operation upon the work when received by the stand, power means on the trucks of said stand and operating the sanding mechanism, spring tensioned balancing means connected with said sanding mechanism, and means for minute adjustment of said sanding mechanism.

3. A machine of the character described comprising a wheeled trucked stand having an opening for the reception of a piece of work when permanently fastened in place, sanding mechanism on the stand and including an endless sanding belt for operation upon the work when received by the stand, power means on the trucks of said stand and operating the sanding mechanism, spring tensioned balancing means connected with said sanding mechanism, means for minute adjustment of said sanding mechanism, and an automatically operated collector associated with said sanding mechanism.

4. A machine of the character described comprising a wheeled trucked stand having an opening for the reception of a piece of work when

permanently fastened in place, sanding mechanism on the stand and including an endless sanding belt for operation upon the work when received by the stand, power means on the trucks of said stand and operating the sanding mechanism, spring tensioned balancing means connected with said sanding mechanism, means for minute adjustment of said sanding mechanism, an automatically operated collector associated with said sanding mechanism, and means for tightening and slackening the belt of the sanding mechanism.

5. A machine of the character described comprising a wheeled trucked stand having an opening for the reception of a piece of work when permanently fastened in place, sanding mechanism on the stand and including an endless sanding belt for operation upon the work when received by the stand, power means on the trucks of said stand and operating the sanding mechanism, spring tensioned balancing means connected with said sanding mechanism, means for minute adjustment of said sanding mechanism, an automatically operated collector associated with said sanding mechanism, means for tightening and slackening the belt of the sanding mechanism, and means slidably supporting the sanding mechanism upon said stand.

6. A machine of the character described comprising a wheeled trucked stand having an opening for the reception of a piece of work when permanently fastened in place, sanding mechanism on the stand and including an endless sanding belt for operation upon the work when received by the stand, power means on the trucks of said stand and operating the sanding mechanism, spring tensioned balancing means connected with said sanding mechanism, means for minute adjustment of said sanding mechanism, an automatically operated collector associated with said sanding mechanism, means for tightening and slackening the belt of the sanding mechanism, means slidably supporting the sanding mechanism upon said stand, and connections between the collector and the power means for the driving of said collector.

7. A machine of the character described comprising a wheeled trucked stand having an opening for the reception of a piece of work when permanently fastened in place, sanding mechanism on the stand and including an endless sanding belt for operation upon the work when received by the stand, power means on the trucks of said stand and operating the sanding mechanism, spring tensioned balancing means connected with said sanding mechanism, means for minute adjustment of said sanding mechanism, an automatically operated collector associated with said sanding mechanism, means for tightening and slackening the belt of the sanding mechanism, means slidably supporting the sanding mechanism upon said stand, connections between the collector and the power means for the driving of said collector, and means for regulating the balancing means.
